(57) **CLAIM**

The ornamental design for a graphic user interface for a display screen, as shown and described.

DESCRIPTION

FIG. 1 is a front view of the graphic user interface for a display screen in a first appearance state; and,

FIG. 2 is a front view of the graphic user interface for a display screen in a second appearance state.

The subject matter in this patent includes a process or period in which the first image changes into the second image. This process or period forms no part of the claimed design.

The broken line showing of portions of the graphical user interface and the broken line showing of the display screen illustrate unclaimed environment and form no part of the claimed design.

1 Claim, 2 Drawing Sheets

FIG. 1

FIG. 2
